UNITED STATES PATENT OFFICE

162,800

LENS TESTING INSTRUMENT

Charles A. Ellis, Southbridge, Mass., assignor
to American Optical Company, Southbridge,
Mass., a voluntary association of Massachusetts

Application December 22, 1950, Serial No. 13,533

Term of patent 14 years

(Cl. D57—1)

To all whom it may concern:

Be it known that I, Charles A. Ellis, citizen of the United States of America, residing at Southbridge in the county of Worcester and State of Massachusetts, have invented a new, original, and ornamental Design for a Lens Testing Instrument, of which the following is a specification, reference being made to the accompanying drawings, forming a part thereof.

Fig. 1 is a side front perspective view of a lens testing instrument showing my new design; and

Fig. 2 is the side elevational view of the opposite side as shown in Fig. 1.

The characteristic features of my new design are shown in full lines in the drawing.

I claim:

The ornamental design for a lens testing instrument, substantially as shown and described.

CHARLES A. ELLIS.
